[57] CLAIM

The ornamental design for the airline telephone handset with digital passenger control functions and video game controls, as shown and described.

DESCRIPTION

FIG. 1 is a first end view of an airline telephone handset with digital passenger control functions and video game control showing my new design;

FIG. 2 is a second end view of the handset with digital passenger control functions and video game controls illustrated in FIG. 1;

FIG. 3 is a bottom plan view of the handset with digital passenger control functions and video game controls illustrated in FIG. 1;

FIG. 4 is a top plan view of the handset with digital passenger control functions and video game controls illustrated in FIG. 1;

FIG. 5 is a left elevation view of the handset with digital passenger control functions and video game controls illustrated in FIG. 1; and,

FIG. 6 is a right elevation view of the handset with digital passenger control functions and video game controls illustrated in FIG. 1.

The broken line disclosure throughout the views is for illustrative purposes only and forms no part of the claimed design.
